OVEN FOR DRYING OR BAKING MOLDS
AND CORES

Carl F. Mayer, Lakewood, Ohio

Application December 2, 1952, Serial No. 323,529

10 Claims. (Cl. 34—66)

1

This invention relates, generally, to that class of industrial ovens that are used for surface drying or for baking green sand molds and cores, thereby to convert them into so-called "skin dried" or "dry sand" molds and cores.

An oven of the particular type with which my present invention is concerned consists of an elongated structure enclosing a tunnel-like passage that is open at its ends and through which the molds and cores are continuously moved by conveying means. Heated gaseous fluid is constantly circulated through a part of the oven, thereby to create a heating zone that usually occupies the greater portion of the length of said passage, and wherein the molds or cores are dried or baked, while a lower temperature fluid, desirably atmospheric air at ambient temperature, is impelled through an adjacent part of the oven, usually substantially the remaining portion of the length of said passage, thereby to provide a cooling zone wherein the molds and cores are cooled to at least a comfortable handling temperature before leaving the oven.

Obviously, other factors remaining constant, it takes longer to bake molds or cores to a dry state, than it does to surface dry them; and it takes longer to dry or bake thick wall molds than those having thin walls, or massive cores, than those of less bulk. Furthermore, the composition of molds and cores that are handled during a particular run of the oven, may differ somewhat from the composition of molds and cores handled at other times, and these diverse circumstances call for heating periods of different duration in order to avoid over or under drying or baking.

As is well known to those acquainted with the type of oven to which the invention pertains, it has heretofore been the practice to alter the drying or baking period by changing the speed of the conveyor. This practice, however, confines the flexibility of the oven, so to speak, solely to the variable speed of the conveyor.

It is a purpose of my invention to increase this range of flexibility by providing also, means for changing the length of the heating zone. In adjusting the oven to the requirements of a particular run, the speed of the conveyor and the length of the heating zone are coordinated to accomplish the highest rate of production with the proper degree of drying or baking.

In view of the various before-mentioned considerations, it is another object of my invention to provide an oven of the type above described including means for conveniently changing the

2

length of the heating zone according to different requirements, and wherein the minimum length cooling zone resulting from the maximum extension of the heating zone is sufficient to cool the work to a handling temperature. The lengthening of the cooling zone, on the other hand, to its full capacity which results from shortening the heating zone as much as possible has no detrimental effect, but rather an advantageous one. In the carrying out of my invention I employ supply duct means and receiving duct means that extend substantially the full length of the oven structure and I desirably arrange them with the supply duct means adjacent the top of the oven passage and the receiving duct toward or at the bottom thereof, although my invention is not particularly limited to this arrangement. Intermediate the ends of the supply and receiving duct means are provisions for dividing each 15 of said duct means into sections of varying lengths, my present preference being a plurality of dampers spaced apart along the respective supply and receiving duct means, with the corresponding dampers of the two duct means in 20 substantially the same vertical plane.

It is another object of my invention to operatively connect corresponding dampers of the supply and receiving duct means so that they may be operated in unison and so that they will open 25 simultaneously and close in the same fashion.

A further object of the invention is to provide mechanism by which all of the dampers are interconnected in such a way that only one of the upper dampers, and the corresponding lower 30 damper, will be closed at any one time; and it is a still further object to include in said mechanism indicating means showing the length of the heating zone and the length of the cooling zone that results from each adjustment of said mechanism.

These and other objects, including simplicity of structure and unique duct arrangement resulting in increased efficiency, are attained in the embodiment of the invention illustrated in 35 the accompanying drawings, wherein:

Fig. 1 represents a longitudinal section through the oven substantially on the line 1—1 of Fig. 4;

Fig. 2 is a fragmentary side elevation, on a scale twice that of Fig. 1, showing the damper adjusting mechanism and the indicating means;

Fig. 3 is a similar view showing the opposite side of the oven and the operative connections between the corresponding upper and lower dampers, and

Figs. 4 and 5 are transverse sections on the

line A—A, looking in the direction of the arrows 4, 4 and 5, 5 respectively.

In the drawings, like parts are designated by like reference characters throughout the several views.

The oven consists of an elongated structure, designated generally by the reference numeral 1, that is made up in most part of a casing composed of a top wall 2, side walls 3 and 4 and end walls 5 and 6, all desirably insulated in the usual way, the latter walls 5 and 6 being provided with an inlet opening 7 and an outlet opening 8, respectively. This casing is supported upon a floor 10 over a pit 11 that is defined by a bottom wall 12, side walls 3^a and 4^a, and end walls 5^a and 6^a, said end walls being spaced a substantial distance from the respective end walls 5 and 6 of the casing, the walls 12 and 3^a to 6^a being of concrete or similar material and integral with the floor 10. It is apparent from the disclosure so far that the walls 12, 3^a and 4^a are parts of the elongated structure 1 that encloses a tunnel-like passage designated A.

Supported within and transversely of the passage A, adjacent the top wall 2 and near the respective end walls 5 and 6, are exhaust ducts 15 and 16, each having branches 17 and 18, respectively, that extend down along the side walls 3 and 4 of the casing, the opposed branches of the exhaust duct 16 continuing substantially to the bottom of said walls, while those of the exhaust duct 15 stop in proximity to the lower end of the inlet opening 7. Said branches are provided with inlet means or slots 19. Projecting laterally from each of the exhaust ducts 15 and 16, through openings in the respective walls 5 and 6, are duct extensions 20 that communicate, through conduits 22, with the inlets of the shells of impellers or blowers 24, shown as driven by electric motors 26. The outlets of the shells of the impellers 24 are arranged to discharge through stacks 28.

Suitably supported at the transverse center of the passage A, and extending along the same adjacent the top wall 2, is a supply duct 30, having outlet openings in its lower side that are spaced apart longitudinally of the duct, said openings being represented at 31. Occupying the top longitudinal corners of the passage A, and desirably co-extensive in length with the supply duct 30, are auxiliary supply ducts or headers 33 that communicate at intervals therewith, with the duct 30 through cross ducts 35, any suitable number being employed. Communicating with and depending from the headers 33 are drop ducts 37 that are spaced apart along the passage A, and are provided with outlet means or openings 38. The duct 30, alone, or in combination with one or more of the ducts and headers communicating therewith, constitutes the supply duct means hereinbefore referred to.

Situated in the lower portion of the structure 1 is a receiving duct means, presently in the form of a continuous duct 40 that is suitably supported midway between the bottoms of the casing walls 3 and 4, and is provided throughout its length with inlet means or openings 41. The duct 40 is shown as terminating adjacent the inlet end of the passage A in the vertical plane of the corresponding end of the supply duct 30, and at its opposite end it projects between the downwardly extending branches 18 of the exhaust duct 16, wherewith it communicates through lateral ducts 42.

The upper or supply duct means, comprising,

in the present instance, the supply duct 30 and headers 33, is provided with dampers 45, 45 and 47, that are spaced apart a substantial distance longitudinally of said duct means. The lower or receiving duct means is equipped with a like number of dampers, designated 46^a, 46^a and 47^a, those of the lower series being directly below the corresponding dampers of the upper series.

While the several dampers may be equipped with individual adjusting means for opening and closing them, I prefer to provide operative connections between the corresponding upper and lower dampers so that they may be operated in unison and in the same manner—that is to say, so that both will be opened or closed at the same time. The corresponding upper and lower dampers may be thought of as a set; and it is a further desire to interconnect the several sets by suitable adjusting mechanism whereby the dampers of only one set will be closed at any one time. To these ends I provide the damper adjusting mechanism illustrated in Fig. 2, and I operatively connect the dampers of each set by the means shown in Fig. 3. Referring to the latter view, the shafts of the dampers 45 and 45^a, where they project beyond the wall 3, have secured to them arms 50 whose distal ends are connected together by a link 51, shown in the present instance as having attached thereto a weight 53. Secured to the shafts of the dampers 47 and 47^a are arms 55, shown as arranged in reverse relation to the arms 50; and the arms 55 are operatively connected by a link 56 on which is shown a weight 58. Fastened to the shafts of the dampers 46 and 46^a are sprocket wheels 60 about which is engaged a chain 62.

Referring now to Fig. 2: gear quadrants 65 and 66 are fastened to the ends of the shafts of the respective dampers 45 and 47, where said shafts extend beyond the wall 4. These quadrants are shown as extending from the opposite sides of the shafts to that from which the arms 50 and 55 project. Accordingly, the weight of said arms and their connecting links and weights, tends to hold the quadrants 65 and 66 against the respective stops 68 and 69. Fastened to the corresponding end of the shaft of damper 46 is a gear segment 70. As will be noted, this segment is in a central position when the damper 46 is closed. It will further be observed that the dampers 46 and 46^a of the central set are closed when those of the other sets are open. A bar 72 is shown as supported alongside the oven wall 4 by guides or rollers 73. A rack 74 on said bar constantly meshes with the gear segment 70. Shorter racks 75 and 76 on the bar 72 are arranged for cooperation with the respective gear quadrants 65 and 66. A lever 78 is pivoted at 79 to the wall 4 and has connection with the bar 72 through a link 80. Accordingly, when the lever is swung on its pivot, as by means of a handle 82, it will move the bar 72 longitudinally.

When the dampers of any one set are closed, they divide the respective supply and receiving duct means into so-called heating and cooling sections which, in turn, determine the length of the heating and cooling zones of the passage A. Accordingly, the length of these zones may be varied by closing the dampers of the different sets, it being remembered that when the dampers of any one set are closed, those of the other sets are open. According to the arrangement of the dampers illustrated in the drawings, the heating zone extends from the vicinity of the inlet

opening 7 of the oven casing to the central set of dampers, or, in other words, to the set comprising dampers 46 and 46^a. It follows, therefore, that the cooling zone extends from the vertical plane of said dampers to near the outlet opening 8 of the oven casing.

Supported upon the oven structure 1, about midway between the ends thereof, is a conventional type of heater 85, fired by oil or other medium. The inlet of the circulating space of the heater is placed in communication with the receiving duct 40 by conduit means 88 that extends across the top of the structure 1 and down the opposite sides thereof and thence inwardly through openings in the side walls 3 and 4 and joins the duct 40, as best shown in Figs. 1 and 4. The outlet of the circulating space of said heater is placed in communication, through conduit means 89, with the inlet of the shell of an impeller or fan designated 90. This impeller or fan is driven by an electric motor 91. The outlet of said shell opens through the top wall 2 into the supply duct 30. It is evident, from the arrangement described, that when the impeller or fan 90 is in operation, gaseous fluid will be withdrawn from the heating zone of the passage A through the duct 40, duct means 88, the circulating space of the heater 85 and duct means 89 into the shell 90, from which it will be expelled into the duct 30, to be distributed throughout the heating zone by said duct and the drop ducts 37.

Surmounting the structure 1 above the cooling zone is an impeller or fan 95 that receives atmospheric air through a pipe 96 that is connected to the inlet of the shell of said impeller or fan. The outlet of said shell has communicative connection through an opening in the top wall 2, with the section of the supply duct 30 in the cooling zone. The impeller or fan 95 is driven by a motor 98 and when in operation draws in atmospheric air and distributes it throughout the cooling zone by way of the section of the supply duct means situated in said zone and including, in the present case, the corresponding sections of the headers 33 and the drop ducts 37 that depend therefrom. At the same time, air is withdrawn from the cooling zone through the section of the receiving duct 40 located therein and this air is exhausted to the atmosphere through the connections previously described, including the exhaust duct 16 and its branches 18 and the adjacent impeller or blower 24.

An endless conveyor 100, schematically illustrated in the drawings, serves to carry the work, which may consist of molds and/or cores, continuously through the passage A, the upper, work-supporting flight of the conveyor entering the passage through the inlet opening 7, and leaving the passage through the outlet opening 8. The conveyor, in the present embodiment of the invention, consists of endless chains that are guided about pairs of large sprockets 102 and 103, mounted on shafts that are journaled in supports shown as located in the pit 11 adjacent the end walls 5^a and 6^a thereof. Occupying an offset of the pit is an electric motor 105 that drives, through a change speed mechanism 106 and a chain or belt 107, the shaft to which the sprockets 103 are fastened. The work-supporting part of the conveyor may be made up of cross bars or rods that are carried by and between the opposed chains of the conveyor. Except in a broad sense, the conveyor constitutes

no part of the present invention, and accordingly it is believed unnecessary to illustrate and describe, in detail, the structural features of the conveyor and its supporting and guiding means.

In the use of the oven, the work is moved at an appropriate speed through the passage A by the conveyor 100, whereon it rests, and while traveling through the heating zone the work is subjected to the hot gaseous fluid that is blasted downwardly and laterally against and about the work by the duct 30 and drop ducts 37. Said fluid is then returned through the section of the receiving duct 40 that is located in the heating zone, and through the duct means 88, to the heater 85, where it is reheated, and from which it is conveyed by the duct means 89 to the shell of the impeller or fan 90. Under the influence of the impeller or fan, the reheated fluid is returned to the heating zone through the supply duct means. As the work continues on through the cooling zone, its temperature is lowered by the atmospheric air that is circulated through said zone in the manner already described.

The exhaust ducts 15 and 16, with their branches, serve to arrest atmospheric air that tends to enter the oven through the openings 7 and 8, and prevent escape of the gaseous fluid from the oven, which latter is laden with vapors that are driven off from the work during the treating process.

In practice, and by way of example, the aggregate length of the heating and cooling zones may approximate 50 feet; and the sets of dampers may be four feet apart, with the central set approximately 34 feet from the receiving end of the heating zone, and, accordingly 16 feet from the exit end of the cooling zone. On this basis I have shown as applied to the side wall 4 of the oven casing, in association with the lever 78 that serves as a pointer, three index marks that have associated with them designations showing the length of the heating zone and the length of the cooling zone when the lever points to any selected one of the index marks. With the damper adjusting mechanism in the position illustrated in Fig. 2, the dampers 46 and 46^a of the middle set are closed, while the dampers of the other sets are open, and as a consequence thereof the heating zone is 34 feet long and the cooling zone 16 feet long, this fact being indicated by the designation "34' H—16' C." When the lever is swung by means of the handle 82 to the left, as the parts are viewed in Fig. 2, until said lever points to the left hand index mark, the gear quadrant 65 will be swung through 90° by the rack 75, which, as previously pointed out, is carried by the bar 72 which has connection with said lever through the link 80, thereby to close the dampers 45 and 45^a. At the same time the rack 74 will swing the gear segment 70 through 90° to open the dampers 46 and 46^a of the middle set. The dampers 47 and 47^a of the third set will remain open for the reason that, under the present circumstances, the rack 76 will move away from the gear quadrant 66 and leave it against the stop 69, and the dampers 47 and 47^a open. Under such an adjustment of the mechanism, the heating zone will be 30 feet long and the cooling zone 20 feet long, according to the designation to which the lever now points. It is evident from what has been said that when the lever is swung to its other extreme position, the dampers 47 and 47^a will be closed, while the others will be open.

This adjustment of the dampers will lengthen the heating zone to 38 feet and shorten the cooling zone to 12 feet.

Thus the length of the heating zone, and consequently the effective duration of the heating period, may be varied according to the requirements of the work being handled.

Having thus described my invention, what I claim is:

1. An elongated oven structure having an inlet opening at one end and an outlet opening at the other and enclosing a through passage, conveying means for continually moving work through said passage, continuous supply duct means opening into said passage substantially throughout the length thereof, continuous receiving duct means communicating with said passage approximately from end to end thereof, means intermediate the ends of each of said duct means by which the latter means may be separated at different selected locations therealong into a heating section and a cooling section, communicative connections between the heating sections of the two duct means, heating and impelling means in said communicative connections arranged to withdraw gaseous fluid from the through passage through the heating section of the receiving duct means and heat said fluid and return it to the passage through the heating section of the supply duct means, air impelling and conducting means for delivering atmospheric air to the cooling section of the supply duct means, and exhaust means in communication with the cooling section of the receiving duct means for withdrawing air from said passage.

2. The combination and arrangement of parts defined by claim 1, and additional exhaust means communicating with the through passage immediately adjacent each end thereof.

3. An elongated oven structure having an inlet opening at one end and an outlet opening at the other and enclosing a through passage, conveying means for continually moving work through said passage, continuous supply duct means opening into said passage substantially throughout the length thereof, continuous receiving duct means communicating with said passage approximately from end to end thereof, means intermediate the ends of said duct means by which each of said duct means may be separated at different selected locations therealong, but at substantially corresponding locations with respect to the other duct means, into a heating section and a cooling section, communicative connections between the heating sections of the two duct means, heating and impelling means in said communicative connections arranged to withdraw gaseous fluid from the through passage through the heating section of the receiving duct means and heat said fluid and return it to the passage through the heating section of the supply duct means, air impelling and conducting means for delivering atmospheric air to the cooling section of the supply duct means, and exhaust means in communication with the cooling section of the receiving duct means for withdrawing air from said passage.

4. The combination and arrangement of parts defined by claim 3, and further exhaust means communicating with the through passage immediately adjacent each end thereof.

5. An elongated oven structure having an inlet opening at one end and an outlet opening at the other and enclosing a through passage, convey-

ing means for continually moving work through said passage, continuous supply duct means opening into said passage substantially throughout the length thereof, continuous receiving duct means communicating with said passage approximately from end to end thereof, a series of dampers in and spaced apart longitudinally of each of said duct means for separating the duct means into heating sections and cooling sections of varying lengths, respectively, means for opening and closing said dampers at will, the individual dampers of the supply duct means being in substantially the vertical plane of the corresponding dampers of the receiving duct means, communicative connections between the heating sections of the two duct means, heating and impelling means in said communicative connections arranged to withdraw gaseous fluid from the passage through the heating section of the receiving duct means and heat said fluid and return it to said passage through the heating section of the supply duct means, air impelling and conducting means for delivering atmospheric air to the cooling section of the supply duct means, and exhaust means for withdrawing the air from the passage through the cooling section of the receiving duct means.

6. An elongated oven structure having an inlet opening at one end and an outlet opening at the other and enclosing a through passage, conveying means for continually moving work through said passage, supply duct means opening into said passage substantially throughout the length thereof, receiving duct means communicating with said passage approximately from end to end thereof, a plurality of dampers in the supply duct means and spaced apart longitudinally thereof, a similar number of dampers in the receiving duct means and spaced apart longitudinally of the latter according to the spacing apart of the former dampers, each damper associated with the supply duct means being in substantially the same vertical plane as the corresponding damper of the receiving duct means and constituting therewith a set, operative connections between the dampers of each set whereby they are caused to move simultaneously and in substantially like manner, the dampers of each duct means being intermediate the ends of said means and being adapted to divide the duct means into a heating section and a cooling section, communicative connections between the heating sections of the two duct means, heating and impelling means in said communicative connections arranged to withdraw gaseous fluid from said passage through the heating section of the receiving duct means and heat said fluid and return it to the passage through the heating section of the supply duct means, air impelling and conducting means for delivering atmospheric air to the cooling section of the supply duct means, and exhaust means for withdrawing air from said passage through the cooling section of the receiving duct means.

7. The combination and arrangement of parts defined by claim 6, and further exhaust means communicating with the passage immediately adjacent the ends of the passage.

8. The combination and arrangement of parts defined by claim 6, and damper adjusting mechanism by which the dampers of any selected set may be closed while the dampers of the other sets are disposed in open position.

9. The combination and arrangement of parts defined by claim 6; and, in addition thereto, damper adjusting mechanism by which the

dampers of any selected set may be closed while the dampers of the other sets are disposed in open position, and indicating means designating the length of the heating zone and the length of the cooling zone resulting from each damper adjustment.

10. The combination and arrangement of parts defined by claim 6; and, in addition thereto, damper adjusting mechanism by which the dampers of any selected set may be closed while the dampers of the other sets are disposed in open position, said mechanism including an element that is moved to different positions when the different sets of dampers are closed, and a designation at each position indicating the length of the heating zone and the length of the cooling zone when said element is in said position.
